DESIGN FOR A SKATING SHOE WITH SKATE ATTACHED THERETO

Walter Ebling, New York, N. Y.

Application July 10, 1940, Serial No. 93,538

Term of patent 3½ years

To all whom it may concern:

Be it known that I, Walter Ebling, a citizen of the United States of America, residing in city of New York, county of New York, and State of New York, have invented a new, original, and ornamental Design for a Skating Shoe with Skates Attached Thereto, of which the following is a specification, reference being had to the accompanying drawing, forming part thereof.

Fig. 1 is a perspective view of a skating shoe with skate attached thereto showing my new design.

Fig. 2 is a side elevational view thereof.

I claim:

The ornamental design for a skating shoe with skate attached thereto, as shown.

WALTER EBLING.
